Primary Examiner — Garth Rademaker*Assistant Examiner* — Katelin G Kloberg(74) *Attorney, Agent, or Firm* — Cook Alex Ltd.(57) **CLAIM**

The ornamental design for a container lid, as shown and described.

DESCRIPTION

FIG. 1 is a top, front, right side perspective view of a container lid, showing my new design;

FIG. 2 is a bottom, rear, left side perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

The broken lines shown in the drawings depict portions of the article and form no part of the claimed design.

1 Claim, 5 Drawing Sheets(56)
